Coty, Inc., Wilmington, Del., a corporation of Delaware

Application April 3, 1939, Serial No. 84,015

Term of patent 3½ years

To all whom it may concern:

Be it known that I, Arthur R. Botham, a citizen of the United States, residing in the city and State of New York, have invented a new, original, and ornamental Design for a Combination Vanity and Lipstick Case, of which the following is a specification, reference being had to the accompanying drawing, forming a part thereof.

In the drawing

vanity and lipstick case.

I claim:

The design for a combination vanity and lipstick case, as shown.

ARTHUR R. BOTHAM.
